HOG SPRAY

Filed Nov. 10, 1926

UNITED STATES PATENT OFFICE.

ALLEN H. ECKERMAN, OF SIOUX CITY, IOWA.

HOG SPRAY.

Application filed November 10, 1926. Serial No. 147,518.

My invention relates to a hog spray of the type in which a gateway is provided through which a hog may pass and mechanism actuated by the gate is adapted to spray oil upon the hog's back as he passes through.

An object of my invention is to provide such a spray which is of simple, durable and inexpensive construction, comprising a gateway, a tank mounted in the gateway and a pump for delivering the oil, including a cylinder and a piston actuated by the swing of the gate in either direction for spraying oil received from the tank.

A further object of the invention is to provide means for adjusting the stroke of the piston in order to regulate the amount of oil delivered from the pump.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is an elevation of the spray, parts being broken away to better illustrate the construction.

Fig. 2 is a sectional view taken on the line 2—2 of Fig. 1.

Fig. 3 is a sectional view taken on the line 3—3 of Fig. 2.

Fig. 4 is a sectional view taken on the line 4—4 of Fig. 2.

I have used the reference character 10 to indicate generally the uprights or side members of a gateway embodying my spray.

The members 10 are connected by a bottom sill 11 and spaced upper cross pieces 12. A frame to support the tank 13 is formed of a horizontal cross piece 14 and side cross piece 15 together with the cross pieces 12.

Oil delivering mechanism comprises generally an oil delivery spout extending downwardly from the tank connected to a pump for withdrawing oil from the tank and ejecting it from the spout and including check valves to control the action of the pump. The spout is thus composed of a T fitting 16 by means of which it is connected to the pump, a sleeve 17 connected to the T fitting 16 by means of a nipple 18, extended through the member 14 and the valves 19 and 20 threaded into the sleeve 17 and nipple 18 respectively. The valve 19 includes a valve element or ball 21 seated to close the open-

ing 22 by means of a spring 23, the latter being held in place by the usual threaded sleeve 24. The tank 13 is secured against a hexagonal flange 24^a on the valve 19 by means of a nut 24^b. The tank may be removed by simply removing the nut 24^b, in order to allow cleaning of the impurities settling to the bottom of the tank from the oil. It will be noted that by projecting the valve into the tank, the bottom layer of fluid will not be drawn off.

The valve 20 includes the valve element 25 seated to close the opening 26 by means of a spring 27 held in place by the threaded sleeve 28; thus it will be seen that the valve 19 upon the suction stroke of the pump will open to allow oil to be drawn into the spout and into the pump while the valve 20 will be closed and that as the pump begins its compression stroke, that the valve 19 will close and the valve 20 will be opened under the pressure, to discharge oil from the opening 29, constituting the nozzle of the device.

It will now be seen that I have provided a very simple arrangement in which the oil container or tank, is conveniently mounted in the gateway directly above the gate and the nozzle projected directly below the tank.

A problem of the present invention has been to provide means for actuating a pump connected with the oil delivery mechanism, just described, in such a way that when the gate is swung in either direction, the oil will be sprayed upon the back of the hog during the outward swing of the gate and will thence be drawn into the pump as the gate swings inwardly. Another problem in connection with the providing of such a spray in which the oil is sprayed upon each outward movement of the gate is that of stopping the swing of the gate so that, as it swings back to its normal position, its momentum will not carry it any substantial distance beyond said normal position.

The first problem is solved in a simple manner by the use of a double armed lever 30 brazed or welded to the shaft 31 which supports the gate 32 and forms an integral part thereof. The shaft 31 is journalled in the sill 11 and the horizontal cross member 14.

The double armed lever 30 is connected to the actuating mechanism of the pump, which will now be described, in such a way that when the gate is swung in one direction one of the arms of the levers functions as a

crank arm to give to the pump spraying its dotted line position and nuts 43 of the mechanism its pressure stroke and when the gate is swung in the other direction, the other arm will so function.

5. The pump includes a cylinder 34 provided with the threaded caps 35 and 36, the former of which is threaded upon the T fitting 16. The cylinder is rigidly secured against the horizontal member 14 by means of a stirrup 36^a encircling the cylinder and extended through the member 14 where it is secured at its ends by screws 36^b. The piston rod 37 is extended through the cap 36 and carries at its end within the cylinder 34 a piston 38.

15. I provide a yoke 39 of strap metal which is slidably mounted in an opening in the upright 10 and which has its arms bent laterally as at 40 and provided with openings 41 to receive the links 42 for connecting the 20 yoke 39 to the lever 30. For the purpose of connecting the links 42 to the flanges 40, they are threaded at their ends and provided with nuts 43 and 44, the latter serving as locknuts. The other ends of the links 42 25 are extended through either of a pair of openings 45 in the respective arms of the lever 30 and there secured as by cotter keys.

46. One of each pair of openings 45 is positioned closer to the shaft 31 than its mate and thereby the length of stroke of the piston can be adjusted since the effective length of the arms of the lever 30 is thus varied by shifting the links 42 from one opening to the other.

35. A spring 47 serves to urge the yoke 39 away from the pump 34 and thus to move the piston 38 in such a direction as to cause the oil to be drawn into the pump cylinder 34.

40. The nuts 43 serve to adjust the tension upon the spring 47. This is essential in order to reduce the swinging of the gate after a hog has passed through. By placing the spring under constant tension, I also 45 eliminate the possibility of any freedom of movement between the links 42 and the yokes 39 which will allow the gate to move without causing the action of the pump immediately.

50. When the gate swings in one direction, such, for instance, as that indicated by the dotted lines at 49, the lever of the arm 30 on that side will pull the link 42 and the yoke 39 in the direction of the shaft 31, thus causing the pressure stroke of the pump. When the gate is swung in the other direction, the other lever will similarly function. The link which is not acting to draw the yoke 39 inwardly, will be moved in the opposite direction and will slide free into its opening 41, the latter opening also allowing the yoke 39 to slide forwardly relative to the link. This is indicated in dotted lines of Fig. 2, the nuts 43 of one of the links being shown in engagement with the member 40 in

its dotted line position and nuts 43 of the other link being shown in a position moved away from the corresponding member 40.

It will now be seen, in connection with the problem of stopping the swing of the gate 70 after an animal has passed through, that the gate must move against the action of the spring 47, each time it moves outwardly in either direction, whereas, in moving toward closed position, it is under the urge of the 75 spring 47. Furthermore, the action of the piston 38 within the cylinder 34 is similar to that of a dash pot in damping the swing of the gate.

The blocks 50, which are secured to the 80 under side of the member 14, serve as guides for the yoke 39 to prevent the side arms, thereof, from spreading and the cap 36 serves as a guide to prevent said arms from collapsing inwardly. The blocks 50, in turn, 85 serve as guides for the yoke 39 to prevent the side arms, thereof, from spreading and the cap 36 serves as a guide to prevent said arms from collapsing inwardly. The yoke 39, in turn, serves as a cage for the spring 90 47 and is aided in this by the opening in the upright 10.

It will be seen that I have provided a very simple arrangement, obtaining all the desirable features of economy of construction, 95 durability, conservation of the fluid used in spraying in a spray utilizing the principle of forcibly spraying the fluid upon the back of a hog as he passes.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. In a spray of the class described, a gateway, a tank supported by the upper portion of the gateway, a depending spout provided with a check valve at either extremity for permitting only downward flow of fluid from the tank, a gate mounted on a vertical axis in the gateway for swinging movement, 110 a pump actuated by the swing of the gate in either direction away from the gateway to eject oil from the spout and by swing of the gate toward the gateway, to draw oil into the spout, and means connecting the pump to the gate, including a spring adapted to urge the gate toward closing position.

2. In a spray of the class described, a gateway, a yoke slidably mounted relative to said gateway, a gate mounted in the gateway for swinging movement in a vertical axis, a tank, a pump for discharging fluid from said tank including a cylinder fixed at one end to the gateway and positioned at its other end between the arms of

the slidable yoke, and including a piston having a piston rod secured to said yoke, a spring between the yoke and the cylinder, and means linking the gate with the yoke 5 to move it toward the pump when the gate is swung away from the gateway.

3. In a spray of the class described, a gateway, a gate mounted in the gateway for swinging movement on a vertical axis, 10 a tank, a pump for discharging fluid from said tank, and means linking said pump with the gate to cause the pump to discharge fluid at each swing of the gate away from the gateway, including a spring serving to 15 return the gate to the gateway.

4. In a spray of the class described, a gateway, a fluid tank, a pump for discharging fluid from the tank, a gate mounted in the gateway for swinging movement, the 20 pump having a movable member, and means connecting said movable member to the gate, including a pair of links connected to the gate in such a manner that one will be moved toward and the other away from, 25 the pump, at each swing of the gate in either direction, the other end of each link having a connection with the movable pump member, allowing it to move freely in one direction only relative to said movable member.

5. In a spray of the class described, a 30 gateway comprising spaced uprights and cross pieces connecting said uprights near their upper ends, said cross pieces being arranged in horizontal and vertical planes to form a box-like frame, a tank received by 35 said frame, a spout secured in the bottom of the tank and extending through the horizontal cross piece, and pumping means connected with the spout and with the gate to cause fluid to be discharged from the tank 40 through the spout upon each movement of the gate away from the gateway.

6. In a spray of the class described, a gateway, a frame forming the upper extremity of the gateway and including a bottom cross member, a gate mounted by the gateway for swinging movement, a tank supported on said cross member, a spout communicating with the tank and extending through the cross member, and pumping 45 means secured to the under side of the cross member and communicating with the spout, said pumping means being connected to and actuated by, the gate.

Signed this 19th day of October, 1926, at 55 Sioux City, in the county of Woodbury and State of Iowa.
